UNITED STATES PATENT OFFICE.

HERBERT GUETTLER, OF CHICAGO, ILLINOIS, ASSIGNOR TO FIBRE MAKING PROCESSES
OF CHICAGO, ILLINOIS, A CORPORATION OF ILLINOIS.

G-PEELER.

1,281,155.

Specification of Letters Patent.

Patented Oct. 8, 1918.

Application filed December 11, 1916. Serial No. 136,192.

To all whom it may concern:

Be it known that I, HERBERT GUETTLER, a subject of the King of Norway, and resident of Chicago, in the county of Cook, State of Illinois, have invented certain new and useful Improvements in Log-Peelers; and I do hereby declare the following to be a full, clear, and exact description of the invention, such as will enable others skilled in the art to which it appertains to make and use the same.

This invention relates to an apparatus for removing bark from logs and particularly to one in which logs of full length may be quickly and easily treated.

Briefly described, the invention comprises a traveling support for holding and agitating a number of logs placed in parallel relation and in the path of water jets whereby the tumbling motion of the logs relative to each other causes the bark to be removed therefrom without the use of knives or other cutting or scraping devices. Associated with the above apparatus are means for controlling the supply of logs to the traveling support and means for removing the same after the bark has been stripped therefrom. The apparatus is also constructed in such a manner as to permit the bark to be conveniently discharged and carried away after being removed from the logs.

The details of construction of the apparatus and other advantages thereof will be more particularly pointed out in the following description of a preferred embodiment of the invention as shown in the accompanying drawings, in which Figure 1 is an elevational view, partly in section, of the entire apparatus, Fig. 2 is a plan view of the same, and Fig. 3 is a detail of construction.

Referring to the drawings in which similar reference characters denote similar parts throughout the several views thereof, the apparatus is mounted on a base 10 which may be constructed of concrete with horizontal platforms 11 and 12, between which is a channel having a sloping side and a vertical side and at the bottom a trough in which is placed the apparatus for carrying away the bark after it has been removed from the logs. On the platform 11 is a frame 13 upon which is mounted an inclined accumulating table or log-deck 14. Logs are conveyed to this deck by a log haul 15 which

may be of any desired construction, but is here shown as comprising belts 16 upon which the logs 17 may be conveyed into position opposite the log-deck 14. The logs may be discharged from the log haul by automatic kickers or in any other manner.

Near the forward edge of the log-deck is a series of stop-levers 18, attached to a shaft 19, which is supported by bearings 20 on upright standards 21 mounted upon the base 10 and braced by suitable tie members 22 connected to the frame 13. The stop-levers 18 may be controlled by any desired mechanism. As here shown the mechanism comprises a gear-wheel 25, mounted at one end of the shaft 19, and meshing with a pinion 26 on a second shaft 27, to one end of which is attached an operating hand-wheel 28. Upon this same shaft 27 is also mounted a ratchet-wheel 29 engaged by a pawl 30, mounted upon a bracket attached to a hub of bearing 20. As shown in Fig. 1, the pawl and ratchet are so related that they normally tend to hold the stop-levers 18 in the position shown. If, however, the pawl 30 is lifted from the ratchet the stop-levers may be controlled by the hand-wheel 28 to permit the desired number of logs to be discharged from the log-deck 17. When it is desired to stop the supply of logs from the deck, the pawl is dropped into place upon the ratchet and the operating wheel 28 turned in the opposite direction to bring the stop-levers into the position shown in Fig. 1, where they will be retained by the pawl 30 engaging the ratchet.

The traveling agitator or apron upon which the operation of removing the bark from the logs takes place is mounted on a frame comprising horizontal members 31 bridged across the channel in the base. At the end near the platform 11 are uprights 32 retained by braces 33 which also serve to support cross bars 34. Similar cross bars 35 are mounted on uprights attached to the horizontal members 31. The crossbars are arranged to support a number of guides 36 over which the moving portions of the agitator travel. Those portions of the guides which are attached to the crossbars 34 are concave, but those portions which are attached to the crossbars 35 are substantially straight. The agitator shown herein comprises two separately movable sections, but it will be understood that only one section 110

or more than two sections may be used if desired.

Each separate section of the agitator comprises a pair of sprocket chains 37 passing over upper sprocket-wheels 38 on a shaft 39 supported in bearings 40 at the ends of the uprights 32 and lower sprocket-wheels 41 on a shaft 42 which is supported in bearings 43 on the horizontal frame member 31. If the agitator comprises more than one section the corresponding driving shafts of each section should preferably be connected by clutches 44. Attached to the chains 37 in any convenient manner are a number of rectangular transverse bars 45 which, as shown most clearly in Fig. 3, are adapted to travel over the guides 36, which are preferably of T-shaped cross-section in order to provide sufficient bearing surface for the transverse bars. At the points where the transverse bars engage guides 36 each bar is provided with a shoe 46 which causes the portions of each bar to be tipped at angles to the surfaces of the guides as the bars are moving over them.

Shaft 39 of one section of the agitator is extended at one end and supported in a bearing on a pedestal 47. This extension of the shaft is provided with a sprocket-wheel 48 over which passes a driving chain 49 connected to gearing 50 having a driving sprocket 51 connected to any appropriate source of power. The gearing is provided with a shiftable pinion 52 by means of which the driving sprocket 51 may be connected to the gearing to drive sprocket-wheel 48 in either direction, thus providing for reversing the direction of travel of the agitator. It will be understood that any appropriate form of driving connection may be used for the above purpose provided it is adapted to be reversed. In addition to sprocket-wheel 48, shaft 39 is provided with a second sprocket-wheel 53 which is connected by means of a chain 54 to a sprocket-wheel 55 on the outer end of shaft 42 of the same section of the agitator. By virtue of this driving connection between the two shafts an amount of slack sufficient to cause the transverse bars 45 to remain upon guides 36 during their travel thereover is always maintained between sprocket-wheels 38 and 41.

The end of the log-deck 14 extends over the upper sprocket-wheels 38 and to prevent any logs or bark from being carried over these sprocket-wheels during the operation of the apparatus an apron 56 depending from the end of the log-deck is provided.

For preventing the logs from rolling off of the traveling agitator during the barking operation a second series of stop-levers 60 upon a shaft 61, and similar to those hereinbefore described, are provided. Corresponding pawl and ratchet mechanism 62, 63 and an operating hand-wheel 64 may be

used for controlling the position of the stop-levers 60. The mechanism of the second set of stop-levers is mounted upon upright standards 65 at the edge of platform 12.

For carrying away the bark after it has been removed from the logs, a conveyer of any appropriate construction passing through the trough may be used. As shown, this conveyer comprises a belt 66 moving over supports 67 in the upper portion of its travel and along the bottom of the trough during the lower portion of its travel.

Upon the platform 12 are mounted two pairs of supporting brackets 68 and 69 having at their upper ends bearings within which shafts 70 and 71 are mounted. Series of sprocket-wheels 72 and 73 are carried by the shafts 70 and 71 respectively, and these wheels are connected by chains 74 which serve to convey the logs away from the agitator after the bark has been removed therefrom. This conveyer may be driven by a sprocket-wheel 75 on shaft 70 over which passes a sprocket-chain 76 leading to any convenient driving mechanism. The conveyer carries the logs to a log haul 77 by which they may be removed. This log haul 77 may be of any preferred construction and is shown as comprising a belt 78 moving within a trough 79. In order to bridge the gap between the lower end of the traveling agitator and the upper surface of the conveyer an inclined table 80 may be placed between the standards 65.

In order to provide water for the logs during the barking operation a pipe 81 having a number of apertures in the lower face thereof is provided immediately above the traveling agitator. The water will issue from the pipe 81 as a spray covering all of the logs upon the agitator.

The operation of the apparatus is as follows:

Logs are brought adjacent the accumulating table 14 by the log-haul 15 from which they may be removed automatically or manually as required. The stop-levers 18 are manipulated at will to supply the logs to the traveling agitator. During the motion of the agitator while logs are upon it, the logs will be subjected to a rotary and tumbling action among themselves, the logs lying immediately upon the bars of the agitator being turned by the action of the upright portions of the transverse angle bars 120 45 and thus communicating their motion to other logs in the pile. The logs will be carried up along the concave portion of the agitator and fall back as they approach the top, thus increasing their tumbling action. Under the agitation thus produced in the presence of water supplied from the pipe 81 the bark will be readily detached and will be carried by the descending water into the channel beneath the agitator where it will 12

be carried away by the conveyer 66. The amount of water that it will be necessary to use during the barking operation will depend upon the wood that is being treated and in the case of some woods may be dispensed with, although it is of advantage for conveying away the bark after it has been removed.

When the bark has been completely removed from the logs the stop-levers 60 are raised to permit the logs to roll off onto the chain-conveyer 74 by which they are carried to the log-haul 77 for transfer to any desired point. If necessary the direction of travel of the agitator may be reversed in order to insure that any logs remaining on the horizontal portion of the agitator may be discharged onto the conveyer. The arrangement of the stop levers 60 near the lower edge of the agitator also permits logs to be discharged individually when during the operation of the apparatus it is found that the bark has been completely removed from some of the logs. This is of advantage as it enables barked logs to be removed to make way for new logs without waiting until all of the logs have been barked.

While the above illustrates a preferred embodiment of the invention it will be understood that various modifications may be made without departing from the principle of the invention.

I claim:

1. In a bark removing machine the combination of an inclined agitator, means adjacent the lower end of said agitator for holding logs upon said agitator and means for moving said agitator to impart a tumbling motion to said logs to remove the bark therefrom.
2. In a bark removing machine, the combination of means for imparting a tumbling action to a plurality of logs disposed parallel to each other to remove bark therefrom, and means for holding logs in place upon said first-named means.
3. In a bark removing machine the combination of a plurality of supports, upper and lower shafts mounted in said supports, and a concave traveling agitator mounted upon said shafts and comprising a plurality of angle bars which engage the logs to impart a tumbling motion thereto.
4. In a bark removing machine the combination of means for holding a plurality of logs in parallel relation to each other, means for moving said first-named means, means for supplying logs to said holding means, and means for discharging logs at will from said holding means after the bark has been removed therefrom.
5. In a bark removing machine the combination of a base, a traveling agitator mounted upon said base and adapted to impart tumbling motion to logs carried there-

on and means adjacent the lower end of said traveling agitator for retaining logs in position thereon but allowing them to be discharged when bark has been removed therefrom.

6. In a bark removing machine, means for imparting a tumbling motion to a plurality of logs placed adjacent each other and maintained in parallel relation to one another, means for holding said logs upon said first-named means and means for supplying water to said logs to aid in the removal of bark therefrom.

7. In a bark removing machine a traveling agitator comprising a plurality of log-engaging members, upper and lower shafts over which said agitator travels, a log haul, a log deck extending over the upper end of said agitator and upon which logs may be discharged from said log haul, means for feeding logs from said log deck to said agitator, means at the end of said log deck and extending adjacent said agitator for preventing logs from being carried over the upper end of the agitator, and means for retaining said logs upon said agitator while bark is being removed therefrom by the tumbling effect of the logs upon one another.

8. In a bark removing machine, an endless inclined traveling agitator and means for retaining logs in position upon the outer inclined surface of said agitator while bark is being removed therefrom by the tumbling action of said logs.

9. In a bark removing machine the combination of means for holding the logs in parallel relation and a traveling curved agitator for tumbling said logs to remove the bark therefrom.

10. In a bark removing machine the combination of a concave upwardly inclined agitator, means for holding logs upon said agitator, and means for moving said agitator to impart a tumbling motion to said logs to remove the bark therefrom.

11. In a bark removing machine an endless concave traveling agitator, and means for retaining logs in position upon the outer concave surface of said agitator while bark is being removed therefrom by the tumbling action of said logs.

12. In a bark removing machine an endless traveling agitator adapted to travel over a horizontal path during a portion of its movement and over a curved path during the remainder of its movement, and means for retaining logs in position upon the surface of said agitator while bark is being removed therefrom by the tumbling action of the logs.

13. In a bark removing machine the combination of a base, a traveling agitator mounted upon said base and adapted to impart tumbling motion to logs carried there-

- 4
- on, means to drive said agitator, means adjacent the lower end of said agitator for retaining logs in position thereon but allowing them to be discharged when bark 5 has been removed therefrom, said agitator being reversible to aid in discharging logs therefrom.
14. In a bark removing machine the combination of an inclined agitator comprising 10 a plurality of separately movable sections each including chains, having transverse angle-bars connected thereto, guides for said bars, wheels over which said chains are adapted to travel, shafts upon which said 15 wheels are mounted, clutches connecting corresponding shafts of each section and means for driving said shafts.
15. In a bark removing machine, the combination of a plurality of supports, an upper 20 shaft mounted in some of said supports, a lower shaft mounted in others of said supports, an inclined guide extending between said shafts, an agitator adapted to be driven from said shafts and pass over said guide 25 and comprising a plurality of angle bars which engage the logs to impart a tumbling motion thereto.
16. In a bark removing machine, the combination of a movable agitator, guides for 30 said agitator each formed with a substantially horizontal portion and a concave portion, means for causing said agitator to travel over said guides and means adjacent the horizontal portion of said guides for 35 retaining logs in place upon the agitator.
17. In a bark removing machine, the combination of a plurality of supports, upper and lower shafts mounted in said supports, 40 guides mounted between said shafts, an agitator driven from said shafts and adapted to travel over said guides, and means for rotating said shafts to drive said agitator.
18. In a bark removing machine, the combination of a plurality of supports, upper 45 and lower shafts mounted in said supports,
- sprocket wheels upon the shafts, guides mounted between said shafts, an agitator driven from said sprocket wheels and adapted to travel over said guides, and means for rotating said shafts to drive said agitator. 50
19. In a bark removing machine, the combination of a base, supports upon said base, shafts in said supports, means for driving said shafts, sprocket wheels on said shafts, chains connecting said sprocket wheels, a plurality of angle bars connected between said chains, a plurality of concave guides for said chains extending between said supports, and means connecting said shafts for driving the same in unison. 55
- 60
20. In a bark removing machine, the combination of a pair of shafts, an agitator passing over and adapted to be moved by the shafts, means for driving said shafts in unison and means permitting logs to be discharged from the agitator over one of the shafts. 65
21. In a bark removing machine, the combination of a pair of shafts, an agitator passing over and adapted to be moved by the shafts, and means permitting logs to be removed from the agitator over one of the shafts. 70
22. In a bark removing machine, the combination of a pair of shafts, one of which is higher than the other, an agitator passing over and adapted to be moved by the shafts, means for driving the shafts in unison to cause a substantially constant amount of slack to be maintained in the agitator, and means whereby logs may be discharged from the agitator over the lower shaft. 75
23. In a bark removing machine, the combination of a pair of shafts, an agitator passing over and adapted to be moved by the shafts, and a plurality of curved arms for controlling the discharge of logs from the agitator. 80
- 85
- In testimony whereof I affix my signature.
HERBERT GUETTLER.
